UNITED STATES PATENT OFFICE

ANDREW FRISTOE NELSON, OF SEATTLE, WASHINGTON

FURNACE

Application filed February 19, 1929. Serial No. 341,252.

My invention relates to a furnace, and particularly to furnaces of the type designed as hot air units for use with oil burners.

Heretofore, it has been the practice in such furnaces, which include a horizontal cylindrical or part cylindrical shell, to fix the front of the furnace, or that portion which supports the doors and their frames, directly upon the head of the horizontal shell at its feed end. The heat within this shell soon becomes intense when the oil burner is started, with the result that the head and its attached front starts to swell, and the doors begin to swing open, due to the warping and twisting of the head, under the expansion and under the unequal distribution of heat. As a result, it is not possible to keep the doors closed properly, which interferes with the draft, and the motion to and fro, caused by this warping, creates noises which are objectionable, especially when the installation is in a residence.

It is my chief object, then, to provide a construction of such furnaces whereby the warping and expansion and twisting of the head of the shell and other associated parts of the furnace proper will have no effect on the furnace front or on the doors and their frames.

A further object is to provide a construction of the front end of such furnaces, which will be simple and inexpensive, and which will enable it to be more readily fitted and held air tight in a shell which customarily surrounds such a furnace.

Other objects will be ascertained from a study of the drawings, specification, and claims forming part of this application.

My invention comprises the novel parts and the novel combination and arrangement thereof, as shown in the accompanying drawings, described in the specification, and particularly defined by the claims terminating the same.

In the accompanying drawings I have shown my invention in a form which is now preferred by me.

Figure 1 is an elevation of the furnace body, the casing being indicated in section.

Figure 2 is in general a section through the front end of the shell.

Figure 3 is an elevation of the front end of the furnace body.

Such a furnace is largely made up of a horizontal part cylindrical drum 1. At its rear end such a drum is finished by the head 55 10, and at its front end a head 11 is fitted in place. The joints may be riveted or welded, preferably the latter. Such a drum is ordinarily supported a slight distance above the floor on which the furnace rests, by aprons 60 12 at each side, which, with the rear end 13, form a chamber which may be lined with fire brick or like refractory material, not shown, and which receives the direct blast from an oil burner such as indicated at B. 65 The gases of combustion are led off through a suitable radiator, that shown herein consisting of the horizontal conduits 14, one at each side of the drum 1 and connected thereto by flues 15 at the rear of the drums, and a common drum 16 connected to the forward end 70 of the drums 14 by flues 17, and leading to a chimney outlet or smoke pipe. It will be apparent that the construction of the radiator, and in fact, the construction of the rear end 75 of the furnace body, is immaterial, inasmuch as my invention is chiefly concerned with the front end of the furnace body.

Ordinarily, the casing C is attached directly to the member corresponding to the 80 head 11 of the drum, by bolting or like means. Not only does this afford communication between the furnace and the air passage and with the exterior as well, permitting soot to collect in the air passages and be distributed 85 throughout the house, but it affords so large an area for the support of these doors, and so directly in association with the heat of the furnace, that these doors and their frames cannot be kept in their proper position, but will warp and move with the head 90 11, and it has been found impossible to keep the doors properly closed and to keep them from making noises which are objectionable. To overcome these two difficulties, then, I 95 have provided a snout, which is secured to the drum and to the aprons 12 so as to form in effect a forward extension of the furnace body, connected to the head 11 inside of its margin, except where it extends downward in 100

continuation of the aprons 12. Thus, as is seen in Figure 2, the head 11 is cut out to leave an opening 18, which is substantially rectangular and which extends from a point below the upper edge of the head to and including its lower edge, and within its side margins. The edges of this opening 18 lie in extension of the two aprons 12 and form thus a rectangular opening extending to the bottom of the shell.

To this opening 18 is fitted a snout, consisting of the front 2, the side walls 20, and the top 21. There may also be a bottom 22 employed if this is found desirable, and similarly, a bottom 19 may form part of the furnace body, at least within the confines of the aprons 12 and 13. This snout may conveniently be made largely of one piece of sheet steel, the front 2 and the sides 20 of the snout being formed integrally and bent to shape, with the top 21 and bottom 22 secured in place, as by welding, and the whole snout welded to the drum 1. In fact, I prefer to form the entire furnace by welding it into a single unit, so that it may be transported and installed as an integral furnace body of one piece. The welds, as between the walls 20 and 21 of the snout and the head 11 of the drum 1, serve to stiffen the various parts and in effect reinforce the angles all of which are welded. This in itself prevents warping of the plates to a certain degree. However, the actual area of the front 2, which is apertured as indicated at 23 and 24, is small and it is spaced forward from the direct heat within the drum 1 and chamber defined by the aprons 12, hence is not so subject to warping as previous fronts, which lie in and include the entire area of the front of the drum, and which are closer to the intense heat. This front 2 is stiffened by the various weld bends and corners referred to above, and may be reinforced and stiffened further by marginal flanges, such as the angle irons 3, which extend about and define the front edges of the plate 2. These are preferably welded in place. To this front 2 are secured the frames 40 and door 4, the oil burner B fitting within the lower frame 40 and closing the aperture 24, while the door closes the aperture 23.

The snout, having less area than the head exposed to the heat within, and stiffened by the several angles, the top 21, and the welds and flanges 3, will not warp appreciably, at least, not to an extent to permit the doors to open or leak, and the flanges 3, in addition to stiffening the snout, permit attachment of the casing without bolt holes between the combustion chamber and hot air passages, so that by no possibility can fumes or soot from the furnace enter the air conduits.

What I claim as my invention is:

1. In a furnace, a shell including a horizontal drum having a head secured thereto at

the front end, and cut away within its top and side margins to define an opening, and a snout comprising two sides, a continuous front and a top fitted and secured to the cut-away edges of said head and projecting forwardly, the front of said snout having apertures adapted to receive doors and their frames, and the sides extending continuously from the top to a point below the drum's lower surface.

2. In a furnace, a shell including a horizontal drum having a head secured thereto at the front end, and cut away within its margins to define an opening which extends downward at the sides to intersect the periphery of the drum, and a snout comprising two sides extending to the floor, a front and a top fitted and secured to the edges of said opening and projecting forwardly, the front of said snout having apertures adapted to receive doors and their frames, and stiffening flanges defining the forward marginal edges of the snout.

3. In a furnace, a shell including a horizontal drum having a head integrally secured thereto at the front end, and an integral snout comprising front, two continuous sides, and a top, secured to the drum's head within its top and side margins, and projecting below the confines of the drum, and forwardly of the head, the head being cut away within the top and sides of the snout to leave an opening of the same size as the snout, the front of said snout having apertures adapted to receive doors and their frames.

4. In a furnace, a shell including a partly cylindrical horizontal drum and an apron depending therefrom at each side, said drum having a head secured thereto at the front end, and having an opening cut therein substantially in upward extension of the aprons, a forwardly projecting snout including two sides, a front, and a top, secured to the margins of said opening, its sides forming a forward continuation of the aprons, and projecting forwardly of the head, the front of said snout having a plurality of apertures adapted to receive doors and their frames.

5. In a furnace, a shell including a horizontal drum having a head integrally secured thereto at the front end, an apron depending from the drum at each side, and an integral forwardly extending snout comprising a front, two continuous sides disposed inside of the sides of the drum, and forming a forward extension of the aprons, and a top disposed below the top of the drum, said snout being secured to the drum's head, and the head being cut away within the confines of the snout to leave an opening to the drum's interior, the front having apertures adapted to receive doors and their frames.

6. In a furnace, a sheet metal shell including a horizontal drum having a head welded thereto at the front end, an apron depending from the drum at each side, a sheet metal

snout extending forwardly from and welded to the drum's head, and comprising a top disposed adjacent but below the drum's top, two continuous sides disposed inside of the 5 sides of the drum but depending therebelow, coplanar with and forming a forward extension of the aprons, and a front welded to the top and sides, and apertured to receive doors and their frames, the head being cut away 10 within the confines of the snout to admit to the drum's interior, and stiffening flanges defining the forward marginal edges of the snout.

7. A furnace shell as in claim 6, the aprons 15 at their rear end terminating short of the rear end of the drum, and an end wall joining the two aprons and secured to the under side of the drum.

8. In combination with a furnace shell as 20 in claim 6, a casing surrounding the same and joined at its forward end to the stiffening flanges.

Signed at Seattle, King County, State of Washington, this 13th day of Feb., 1929.
